UNITED STATES PATENT OFFICE.

MAX HERSKOVITZ, OF CHICAGO, ILLINOIS.

HANGER FOR LIGHT-REFLECTING BOWLS.

1,262,046.

Specification of Letters Patent.

Patented Apr. 9, 1918.

Application filed September 21, 1917. Serial No. 192,441.

To all whom it may concern:

Be it known that I, MAX HERSKOVITZ, a citizen of the United States, and a resident of Chicago, county of Cook, and State of

5 Illinois, have invented certain new and useful Improvements in Hangers for Light-Reflecting Bowls, of which the following is declared to be a full, clear, and exact description.

10 This invention relates to hangers for light reflecting bowls, and its principal object is to provide a hanger that may be securely fastened to a glass or other transparent or semi-transparent bowl without danger of

15 cracking it. Another object is to provide a hanger with a flexible electric light socket support that may be readily bent in any direction, whereby the electric light socket may be held in any position desired. The

20 invention consists in the several novel features hereinafter fully set forth and claimed.

The invention is clearly illustrated in the accompanying drawing, in which:

Figure 1, is a vertical section of a light reflecting bowl, showing a simple form of a hanger embodying the present invention applied thereto; Fig. 2, is a face view of the hanger looking in the direction of the arrow 2, in Fig. 1; Fig. 3, is a perspective view of 25 the inner bowl engaging member detached from the outer member, and Fig. 4, is a side elevation of a modified form of the hanger.

Referring to said drawing, 5, designates the outer bowl engaging member of the 30 hanger which may be of any suitable and ornamental design. Said member may be formed with one or more branches 6, 7, in the form of hooks, to which may be attached chains or other supporting devices.

40 In accordance with the common practice, three hangers are employed for each bowl, and chains or other supporting devices (not shown) are secured to the hooks 6, and support the bowl. The member 5, is formed

45 with laterally extending wings 8, which are arranged to enter the usual groove 9, formed below the outturned edge 10, of the bowl A. The member 5, has a branch 11, which is arranged to extend over and down on the in- 50 side of the bowl, and in the lower end of the said branch 11, is threaded a clamping screw 12, which projects toward the wings 8, of the member 5.

Secured to the branch 11, of the outer 55 member 5, is a bendable and flexible inner bowl engaging member 13, which is located

between the branch 11, and wings 8, of the outer member 5. In its preferred form, said bendable and flexible cushioning member 13, is pivotally secured to the branch 11, as for 60 instance by lugs 14, that extend out laterally from both sides of the branch and enter holes in ears 15, bent up from the upper end portion of the member 13. Said member 13, may comprise a narrow strip of light gage 65 sheet metal, having two laterally extending branches or ears 16, which are bent toward the bowl, and act as cushioning members between the clamping screw and bowl. The member 13, may extend down below the 70 cushioning ears 16, as at 17, to provide a holder for an electric light socket (not shown) and the lower end of said extension 17, may be formed with an eye 18, for the reception of the threaded connection for the 75 socket. In practice, the inner bowl engaging member 13, may be stamped up flat, the ears bent up, and the shape of the main body portion may then be bent up to accommodate the shape of the bowl, and the 80 socket holding extension 17, may be bent into any desired shape to accommodate the electric light socket and bulb, or it may be twisted as seen in dotted lines in Fig. 1. When applied to the bowl, the clamping 85 screw 12, is screwed up against the member 13, and because of the flexibility of the cushioning ears 16, it may be screwed up tightly, since the ears will yield under the pressure, and consequently any danger of 90 cracking the bowl, is eliminated. Furthermore, this construction and arrangement affords two points of contact of the inner bowl engaging member against the inner face of 95 the bowl.

In the modified form illustrated in Fig. 4, the supporting member 5^a, is of the type known as the gravity hanger, and it has the usual hook 6^a, and bowl engaging branch 9^a, which underlies the outturned edge at the 100 top of the bowl. It also has the branch 11^a, which extends down on the inside of the bowl, and holds the clamping screw 12^a. The inner bowl engaging member 13^a, may be of the same construction as in the preferred form. In this modified form, the clamp screw bears against the inner bowl engaging member 13^a, and presses the yielding cushioning ears against the inner face of the 105 bowl.

110 From the above, it is readily apparent that in place of having the clamping screw

bear directly against the fragile bowl, with the attendant danger of cracking the same, a cushioning device is interposed between the screw and bowl, which effectively prevents 5 cracking of the bowl when the screw is screwed up tight.

More or less variation of the exact details of construction is possible without departing from the spirit of this invention. I desire, 10 therefore, not to limit myself to the exact details of construction, but intend in the following claims to point out all of the invention disclosed herein.

I claim as new, and desire to secure by 15 Letters Patent:

1. A hanger for light reflecting bowls comprising pivotally-connected outer and inner bowl engaging members, the inner member being flexible and adjustable toward 20 and away from the outer member and means for pressing said inner member against the bowl.

2. A hanger for light reflecting bowls comprising a clamp arranged to straddle 25 the upper edge of the bowl, and formed with bowl engaging members for engaging the outer face of the bowl, a clamping screw mounted on the part which extends within the bowl, and a cushioning member pivoted 30 on said clamp and interposed between the clamping screw and bowl.

3. A hanger for light reflecting bowls, comprising pivotally-connected outer and inner bowl engaging members, the inner 35 member being flexible and adjustable toward and away from the inner face of the bowl, said outer member having a branch adapted to extend down on the inside of the bowl, and a clamping screw mounted in said 40 branch and adapted to bear against said inner bowl engaging member.

4. A hanger for light reflecting bowls comprising outer and inner bowl engaging members, the outer member having a branch 45 adapted to extend down on the inside of the bowl, said inner bowl engaging member being flexible and bendable and pivotally secured to said branch, and a clamping screw mounted in said branch and arranged 50 to bear against said inner bowl engaging member.

5. A hanger for light reflecting bowls comprising outer and inner bowl engaging members, the outer member having a branch 55 adapted to extend down on the inside of the bowl, said inner bowl engaging member being pivotally secured to said branch and having laterally projecting flexible bowl engaging ears, and a clamping screw mounted 60 in said branch, and arranged to bear against said inner bowl engaging member.

6. A hanger for light reflecting bowls

comprising outer and inner bowl engaging members, the outer member having a branch adapted to extend down on the inside of 65 the bowl, said inner member being pivotally secured to said branch, and having flexible bowl engaging means and a bendable electric light socket holder, and a clamping screw mounted in said branch, and arranged to 70 bear against said inner bowl engaging member.

7. A hanger for light reflecting bowls comprising outer and inner bowl engaging members, the outer member having a branch 75 adapted to extend down on the inside of the bowl, said inner bowl engaging member being pivotally secured to said branch, and being composed of a single flexible and bendable piece formed with resilient bowl 80 engaging members, and an electric light socket holder, and a clamping screw mounted in said branch and arranged to bear against said inner bowl engaging member.

8. A hanger for light reflecting bowls 85 comprising an outer bowl engaging member having two spaced places for contact with the outer face of the bowl, and a branch adapted to extend down on the inside of the bowl, and a flexible and bendable inner bowl 90 engaging member pivotally secured on said branch and having two flexible places for contact with the inner face of the bowl, and an extension forming a support for an electric light socket, and a clamping screw 95 threaded in said branch and arranged to bear against said inner bowl engaging member.

9. A hanger for light reflecting bowls comprising an outer bowl engaging member 100 having a branch adapted to extend down on the inside of the bowl and having oppositely disposed lugs formed thereon, a flexible and bendable inner bowl engaging member formed of a single piece having perforated ears at one end pivotally secured 105 on said lugs, and laterally projecting bowl engaging ears, and a clamping screw threaded in said branch and arranged to bear against said inner bowl engaging member. 110

10. A hanger for light reflecting bowls comprising an outer bowl engaging member having a branch adapted to extend down on the inside of the bowl, and having oppositely disposed lugs formed thereon, a flexible and bendable inner bowl engaging member formed of a single piece having lug 115 engaging ears, bowl engaging ears and an electric light socket holding arm, and a clamping screw threaded in said branch and arranged to bear against said inner bowl 120 engaging member.

MAX HERSKOVITZ.
